CLAIM

The ornamental design for a golf cup putting aid, as shown and described.

DESCRIPTION

FIG. 1 is a top plan view illustrating my new design for a golf cup putting aid;

FIG. 2 is an inverted rear edge view taken in the direction of arrow 2 in FIG. 1;

FIG. 3 is a front edge view taken in the direction of arrow 2 in FIG. 1;

FIG. 4 is a left side edge view taken in the direction of arrow 4 of FIG. 3, the opposite side edge being a mirror image thereof;

FIG. 5 is a bottom plan view taken in the direction of arrow 5 in FIG. 4;

FIG. 6 is a top plan view of half of my new design taken in the direction of arrow 6 in FIG. 3; and,

FIG. 7 is a view taken in the direction of arrow 7 in FIG. 6.

FIG. 2**FIG. 1****FIG. 3****FIG. 4****FIG. 7****FIG. 5****FIG. 6**
